UNITED STATES PATENT OFFICE.

ALFREDO MARONE, OF SANTA VITTORIA D'ALBA, ITALY.

LIQUID-LEVEL INDICATOR.

Application filed September 1, 1921. Serial No. 497,695.

To all whom it may concern:

Be it known that I, ALFREDO MARONE, a subject of the King of Italy, residing at Santa Vittoria d'Alba, Province of Cuneo, Italy, have invented certain new and useful Improvements in Liquid-Level Indicators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to a device for indicating the level of the cooling water in radiators of internal combustion engines for motor cars or the like.

This device consists of a receptacle which 20 is preferably integral with the stopper or cap closing the filling orifice of the radiator and that has its walls partially made of a transparent material and is ended by an emptying tube. The said receptacle which 25 is filled with liquid, becomes positioned in a reversed position, when the stopper or cap is screwed on, its emptying tube being immersed in the water contained in the radiator. According to a modification of this de- 30 vice the transparent receptacle is provided in addition to the emptying tube with a tube for the admission of air, the said tube rising in the receptacle up to the highest part of the latter and is immersed in the 35 water contained in the radiator to a depth corresponding to the minimum level of water in the radiator which is required for a good working of the engine. Owing to this arrangement when the level of the water in 40 the radiator falls below the minimum level aforesaid a free flow of the liquid contained in the receptacle takes place and the absence of this liquid shows that the said level has been lowered.

45 A few modes of construction of the object of the invention have been illustrated by way of example only in the accompanying drawings in which:

Fig. 1 is a vertical section of a first form 50 of construction of the indicating device;

Figs. 2 and 3 show a front elevation and a transverse section of a modification of the same device; —Fig. 4 shows a second mode of construction of the same device.

55 Referring to the first form of construction shown in Fig. 1, the device consists of a

hemispherical receptacle 1 made of glass, integral with a cap or stopper 2 closing the filling orifice 3 of the radiator 4.

The fixing of the receptacle 1 to the said stopper 2 may be effected in any way; in the form shown in the drawing a collar 1' of the receptacle is fixed inside a recess 2' of the stopper 2 by means of cement 5.

60 The receptacle is completed by an emptying tube 6 leading to the said recess 2' of the stopper 2 and having a suitable length so as to be immersed into the water 7 contained in the radiator when the stopper 2 is screwed on to the orifice 3.

65 The lower end of the emptying tube is preferably obliquely cut at 6' in such a manner as to facilitate the flow of the liquid 8 which is to be contained by the receptacle.

70 According to the modification shown in 75 Figs. 2 and 3 the receptacle containing the liquid 8 forms an integral part of the stopper 2, the said receptacle consisting of an annular body 2'' projecting from the upper part of the stopper and closed on its two 80 faces by means of glass plates 1''.

According to the second mode of construction of the device shown in Fig. 4 the receptacle, consisting for instance of the annular body 2'' integral with the cap or stopper 2 closed on its two faces by glass plates 1'', is provided in addition to the emptying tube 6, with a tube 9 rising up to the highest part of the receptacle and immersing in the water 7 contained in the radiator 4 to a 90 depth corresponding to a minimum level —x.x—of the water in the radiator which is required for a good working of the engine.

95 The device operates as follows: With reference to the first mode of construction shown in Fig. 1 and its modification shown in Figs. 2 and 3, first of all the receptacle 1 is filled with liquid, preferably water, by immersing, for instance in water, the whole of the stopper 2 and of the receptacle.

100 The stopper is afterwards screwed on to the orifice 3; during this operation it may happen that owing to a sudden tipping over of the receptacle some of the liquid escapes through the tube 6 but this has no importance because for the working of the whole arrangement it is not necessary that the receptacle 1 shall be entirely filled. Once the stopper 2 placed in position, the tube 105 6 becomes immersed into the water 7 contained in the radiator and which is supposed

to rise to the level required for good working of the engine. Under these conditions the liquid 8 contained in the receptacle 1 cannot leave the latter and its presence which 5 can be ascertained easily by the driver of the vehicle from his seat serves to indicate that the water in the radiator is maintained at the required level.

On the contrary if the level falls below 10 the outlet orifice 6' of the tube 6, then the liquid 8 falls freely and entirely from the receptacle 1. The absence of liquid inside 15 1, which can also be seen from the driver's seat, indicates that the level of the water in the radiator has fallen below the value required for a good working of the motor.

Referring now to the mode of construction shown in Fig. 4 the working is as follows:

20 When the water in the radiator tends to fall below the level —x.x— the lower orifice of the tube 9 is left uncovered. Air penetrates then inside the receptacle 1'', 2'' and produces a rapid flow of the liquid 8 out of 25 the receptacle, the said liquid being discharged through the tube 6. The absence of the liquid 8, is therefore, a proof of the lowering of the level of the liquid 7 in the radiator.

30 According to the form of construction shown in Fig. 4 the length of the tube 6 has no importance because what determines 35 the emptying of the vessel 1'', 2'' when the level of the liquid in the radiator falls below a certain limit, is the predetermined length of the tube 9. With this form of construction the emptying of the receptacle 1'', 2'', is more rapidly effected owing to the fact that air penetrates freely inside the said

receptacle through the tube 9. Also the 40 initial filling of the said receptacle with liquid 8 is much facilitated.

I wish it to be understood that the details for carrying the invention into effect 45 may be modified in various respects without in any way departing from the spirit of the invention.

I claim:

1. A radiator cap having a threaded portion and a glass portion, both readily removable as a unit from a radiator, two tubes connected to said cap both of which have their lower ends extending into the liquid in the radiator, the upper end of one of which tubes extends above and the other below the liquid level in said glass portion, a partial vacuum being maintained in said glass portion under all conditions of normal liquid level indication. 50

2. A liquid level indicator comprising a 60 transparent liquid receptacle arranged above the level of the liquid whose level is to be indicated and having a depending tube, and an air vent tube extending normally above the liquid in said container, both tubes being normally liquid sealed by the liquid whose level is to be indicated. 65

3. A radiator cap comprising an inverted closed water receptacle in which the liquid is visible and a depending discharge tube 70 and an air vent tube whose upper end extends above the level of the water in said receptacle the lower end of which is bevelled and extends into the water in the radiator to a lesser depth than said discharge tube. 75

In testimony that I claim the foregoing as my invention, I have signed my name.

ALFREDO MARONE.
